OIL BURNER

Antonio Fransosi, Providence, R. I.

Application August 31, 1931. Serial No. 560,261

5 Claims. (Cl. 158—83)

This invention relates to a fuel oil burner and is in continuation in part of my co-pending application, Ser. No. 387,413, filed August 21, 1929.

One of the objects of this invention is to provide a burner with an improved supporting base which may be individually adjustable for each of the burner units.

Another object of the invention is the provision of an inlet opening located out of registry with the conduit connecting two of the annular fuel chambers.

Another object of the invention is the provision of a brace plate extending across the burner to support the fuel chambers and reinforce the inlet opening.

Another object of the invention is the provision of a brace plate which cooperates with the support standard for mounting the burner thereon.

A further object of the invention is the provision of a preheating reservoir which may be swung from beneath the fuel chambers for the reception of preheating fuel.

A still further object of the invention is the utilization of the connections between the annular fuel chambers as a means for conducting fuel from one to the other.

With these and other objects in view, the invention consists of certain novel features of construction, as will be more fully described, and particularly pointed out in the appended claims.

In the accompanying drawing:

Fig. 1 is a top plan view of the burner with the perforated cylindrical tubes which are used in connection therewith removed.

Fig. 2 is a section through the fuel chambers of the burner showing the preheating reservoirs swung from their position beneath the burner for the reception of fuel.

Fig. 3 is a side elevation of the structure shown in Figure 1.

Fig. 4 is a sectional view at right angles to the showing of Figure 3, and illustrating the pivotal mounting of the preheating reservoirs.

Fig. 5 is a section on line 5—5 of Figure 4.

Fig. 6 is a top plan view of one of the preheating troughs.

It has been found desirable in the use of range oil burners to provide a support for the individual units which may be readily adjustable to locate the burner at the desired height. It is also desirable to provide a construction which will minimize the carbon deposit, and a construction by which the burner may be preheated for ignition without using wicks; and this is accomplished

through a long range which may be adjusted at the desired height. I have arranged an inlet opening so that it will be at a point spaced from the connection between the annular chambers; and I have provided preheating troughs beneath the burner to swing therefrom for the reception of fuel for preheating. I have also provided the brace plate in such a manner as to support the burner and strengthen the inlet opening as well as permit the support standard therefor to extend therethrough, a considerable extent where a wider range of vertical adjustment may be accomplished; and the following is a detailed description of the present embodiment of this invention, illustrating the preferred means by which these advantageous results may be accomplished.

With reference to the drawing, 10 designates the burner base which is generally triangular in shape and provided with bolts 11 extending therethrough to form adjustable feet for the base to level the same on the bottom of the stove or other support upon which it may be located. An opening 12 is provided in the base and a collar 13 extends upwardly therefrom for the reception of a support standard 14 which is held in adjusted position in the collar and base by means of a set screw 15.

The burner consists of a cast body providing an inner annular chamber 16 and an outer annular chamber 17 with bridge members 18 extending between the annular chambers at spaced points for connecting them together, and I utilize the brace members to provide conduits 19 through each of these brace members 18 for connecting the annular chambers 16 and 17, so that fuel may flow through the conduits 19 from one chamber to the other. A brace plate 20 extends diametrically across the inner annular chamber and is provided with an opening 21 from which there extends a collar 22 for the reception of the support standard 14 which extends through the collar and opening and is held therein by a set screw 23 to hold the standard in adjusted position. This standard may be of any desired height to project through the opening 21 and collar 22 to provide a long range of adjustment.

The brace member 20 is located out of line with the opposite bridge members 18 and at one end of the brace plate there is provided an inlet opening 24 connected to the inner annular chamber 16 for the supply of fuel thereto through the conduit 25 which includes suitable sediment trap 26 provided at its end. The fuel opening 24 is thus located intermediate two of the conduits 19 and 20.

is substantially midway therebetween, and I find that by this arrangement less carbon is formed in the use of the burner than where the inlet opening is located closely adjacent one of the conduits between the annular chambers.

It will be understood that in use, perforated cylindrical members rest upon the shoulders 27 on either side of each of the annular chambers to provide combustion chambers and assist in the 10 burning of the oil, all of which is customary and well known.

The oil which burns after the burner is heated, burns as a gas, although in order that the burner may be started, it is usually necessary to provide 15 a wick projecting from the fuel chambers; but in order that a wick may be eliminated, I have provided a pair of preheating troughs 28 and 29, having lug portions offset in different vertical planes, as shown in section in Figure 4, these lug portions 20 being pivoted on the post 30 secured to the brace member 20. These troughs are arcuate in shape and extend horizontally in a unilateral plan due to the provision of the above mentioned offset portions and they fit beneath the burner so that the 25 fuel therein when ignited will heat the burner for the starting of the same. It will be noted by referring to Figures 3 and 4 of the accompanying drawing that when the preheating troughs are in operative position they extend entirely within the 30 periphery of the burner proper for the reason that the transverse dimension of the troughs is substantially equal to the transverse dimension of the burner. These troughs are each usually provided with a filling of asbestos to assist in the 35 burning of the oil and each may be swung from beneath the burner on the pivot 30 to expose the same for loading with fuel prior to ignition.

I have illustrated two of such preheating troughs or reservoirs, although I find in many instances it is necessary to use but one by which construction I eliminate the use of wicks in the 40 burner.

The foregoing description is directed solely towards the construction illustrated, but I desire it 45 to be understood that I reserve the privilege of resorting to all the mechanical changes to which the device is susceptible, the invention being defined and limited only by the terms of the appended claims.

50 I claim:

1. A device of the character described, comprising an annular fuel burner, a brace member for said burner, a support for said burner extending through said brace member, a pair of arc-shaped 55 preheating troughs disposed in a unilateral plane beneath said burner, an offset pierced lug at one end of each said troughs and a stud adjacent said support and carried by said brace member, and receivable in said lugs for pivotally mounting said troughs.

65

70

75

2. A device of the character described, comprising a horizontally disposed ring-shaped fuel burner, a brace member therefor, a support for said burner extending through said brace member, a pair of horizontally disposed arc-shaped troughs adapted to be positioned in a unilateral plane beneath said burner, an offset pierced lug at one end of each said troughs, said lugs being offset in different vertical planes with respect to each other and to their respective troughs, whereby to overlie one another while maintaining the unilateral position of said troughs, and a single stud receivable within said pierced lugs for pivotally mounting said troughs on said brace member, whereby the latter may be swung beyond the outer periphery of the burner. 80 85 90

3. A device of the character described, comprising a ring-shaped fuel burner, a brace member therefor, a support for said burner extending through said brace member, an arc-shaped trough having a transverse dimension substantially equal to the transverse dimension of said burner, a lateral inwardly offset lug at one end of said trough and means carried by said brace member inwardly of the inner periphery of said burner for pivotally mounting said trough, whereby the latter in one position will lie parallel to said burner to have its curved walls substantially aligned with the inner and outer peripheries of the burner. 95 100 105

4. A device of the character described, comprising a ring-shaped fuel burner, a brace member therefor, a support for said burner extending through said brace member, a pair of arc-shaped troughs having a transverse dimension substantially equal to the transverse dimension of said burner, and a single means for pivotally mounting said troughs on said brace member in a unilateral plane beneath said burner, whereby said troughs will align with the peripheral walls of said burner 110 in one position and also being capable of swinging outwardly beyond the outer periphery of the burner. 115

5. A device of the character described, comprising a ring-shaped fuel burner, a brace member therefor, a support for said burner extending through said brace member, a pair of arc-shaped troughs having a transverse dimension substantially equal to the transverse dimension of said burner, and the combined length of said troughs 120 approximating the circumferential dimension of said burner, and a single means carried by said brace member for pivotally mounting said troughs in a unilateral plane beneath said burner whereby said troughs will align with the peripheral walls 130 of said burner in one position and also being capable of swinging outwardly beyond the outer periphery of the burner. 125 130 135
